CONTAINER OR SHIPPING CASE HAVING A
REMOVABLE COVER TO BE LOCKED AND
SEALED

Joseph Burger, New York, N. Y.

Application December 30, 1943, Serial No. 516,151

1 Claim. (Cl. 217—56)

1

The present invention relates to containers or shipping cases and more particularly to those having removable tops or covers which can be locked and sealed and so constructed and arranged that they may be so used repeatedly.

Under conditions now existing it is not possible to make containers or shipping cases from inexpensive materials, such as corrugated paper or cardboard, from which materials were formerly made those shipping or packaging containers intended to be thrown away after use, since these materials are not longer available. As a result, shipping containers or packing cases of this type must now be made of more costly materials, such as wood, making them relatively expensive to discard.

I have provided a container, the top of or cover to which, although locked and sealed, may readily be opened to remove the goods shipped in the container but which is so designed that it may then be returned to the shipper for repeated similar use. As a result, containers or shipping cases embodying my invention, even though made from comparatively expensive materials, are yet comparatively inexpensive since they may be used over again a great many times, making available for commerce more durable and stronger containers, which heretofore because of cost were not used in a great many services.

Further, containers or packing cases embodying my invention are so constructed and arranged that they are tamper-proof because the cover thereof cannot be removed without breaking a seal, which if broken would immediately indicate to the receiver that the container or packing case had been opened.

Heretofore, wooden boxes or cases could not readily be reused, since the top or cover thereof is usually nailed or so secured to the box or case that it must of necessity be destroyed or so damaged when it is opened that it is no longer reusable.

My invention, on the other hand, when applied to the prior box or shipping case construction provides one which can be sealed and readily opened without any damage thereto so that the box or case may be reused as often as desired.

These, other and further objects, advantages and uses of my invention will be clear from the following description and the drawing relating thereto, in which

Fig. 1 is a top plan view of a container or shipping case according to my invention, partially broken to show a groove and one of the seals

2

partially broken away show the catch member holding means therebeneath;

Fig. 2 is a section on the line 2—2 of Fig. 1;

Fig. 3 is a sectional view similar to Fig. 2, with the top or cover removed;

Fig. 4 is a section on the line 4—4 of Fig. 1;

Fig. 5 is a top plan view of the top or cover, showing the locking members in position to permit the closure to be removed from the container or case.

Referring now to the drawing, the box or shipping case 10 may be made of any suitable material, preferably wood, and is provided with the bottom 12, the end walls 14 and sides 16, which may be secured together by any suitable well known means, such as glue, nails or screws. It will, of course, be understood that the present invention may be applied to any construction of box or case, the details of construction, except as modified as hereinafter described, forming no part of the invention.

The interior 18 of the box or shipping case 10 is closed by the cover 20, which rests on the upper edges of the end liners or end cover supports 22 and side liners or side cover supports 24 secured to the container or case in the interior thereof, the liners or supports extend inwardly from the ends 14 and sides 16 beyond the upper shoulder 26 forming the locking groove 28, to which further reference will be made.

The dimensions of the cover or closure 20 are such that it fits close to the ends 14 and sides 16 but does not extend into the locking groove 28 so that the cover or closure may be lifted out through or fitted into the opening 30 to the interior of the container or case to open or close it.

The cover or closure 20 has pivotally arranged thereon the locking members 32, which are secured to the cover or closure by any suitable means, such as the rivets 34, which constitute pivots about which the locking members may be swung into locking and unlocking position, as indicated by the arrows 36 (Figs. 1 and 5) and which function will be further explained.

The ends 38 of the locking members 32 are preferably somewhat beveled so that they will relatively tightly fit into the grooves 28, when the members are swung about the pivots 34 into locking position against the stop members 40, which are secured to the cover or closure 20 by any suitable means.

The locking members 32 are longer than the width of the cover or closure 20 so that the beveled ends 38 extend completely into the groove 28 when the members 32 are positioned by cor-

responding, adjacent stops **40** transversely of the cover or closure (as illustrated in Fig. 1), the stops arranged on the closure or cover relatively to the locking members to accomplish this.

For convenience in the manufacture of the container, the locking grooves **28** are arranged along the sides **16** extending from one end of the container or case to the other end thereof, though it will be understood that these grooves need only be long enough and properly spaced to permit the entry therein in locking position of the beveled ends **38** of the locking members **32**.

In operation, after the box or shipping is packed and the cover or closure locked in position by swinging the beveled ends **38** of the members **32** into the groove **28**, whereupon the case or container will not be opened unless the members are purposely moved into a position such as illustrated in Fig. 5.

In order to prevent tampering with the case and unauthorized removal of its contents during transit, I provide means for locking a member **32** to a stop **40**, in the container closing position illustrated in Fig. 1.

A comparatively inexpensive construction to accomplish this is to provide an opening **42** in each stop **40** and a corresponding opening **44** in each member **32**, the openings being brought into parallel alignment upon bringing home against its corresponding stop **40** a member **32**. A catch member **46**, such as a U-shaped staple, one leg **48** of which is arranged in the stop member opening **42** and the other leg **50** of which is arranged in the aligned opening **44** of the corresponding locking member **32**, prevents these members from being moved into the position illustrated in Fig. 5, whereat the ends **38** have been moved out of the grooves **28** to thereby permit removal of the cover or closure **20** from the container or case.

This catch member or lock **46** may then be sealed as by the metal or paper seal **52**, which covers and holds the catch member or lock in position and which seal is preferably cemented to the stop and locking members. Should the seals be removed or in any way broken or damaged that would establish immediate evidence of possible tampering with the contents that had been shipped, so that in such event the shipment need not be accepted.

When the shipment is received, the seals are broken to release the catch member or lock for

removal from the stop and locking members so that the container can be opened and the contents removed, whereupon the container may be closed, as described, the catch member or lock resealed so that it will not be lost and the container returned to the shipper for reuse.

It will now be recognized that I have provided a shipping container or packing case which will in no way be damaged when it is opened to remove its contents, even though it had been sealed to prevent tampering therewith or unauthorized removal of its contents, so that it may be used again and again, as desired, making possible for its construction heretofor unused relatively expensive and durable materials.

While I have described in specific detail the construction of an embodiment of my invention, I do not intend to be limited thereto but intend to claim the invention as broadly as the following claim and the state of the prior art will permit, since changes in the construction details thereof will now readily occur to those skilled in the art.

I claim:

A shipping case comprising a bottom, end walls, side walls and a removable closure therefor, said side walls having grooves therein, locking members pivotally secured to the closure, stop members fixed to the closure and extending substantially at right angles to the grooves upon arranging the closure in the case, each of said locking members to be swung about its pivot into locking position against a stop member with the ends of the locking member inserted in a said groove, each of said stop and locking members having holes therein, the mouth of the hole in a stop member lying in the same horizontal line as the mouth of the hole in the locking member upon bringing the locking member against a stop member, a U-shaped member, the legs of which completely and removably extend into a hole in the stop member and into the hole of the corresponding locking member, the element of said U-shaped member connecting the legs thereof being positioned on and against the top of the stop member and corresponding locking member and a flat sealing member secured to the surface of the stop member and corresponding locking member and extending partially thereover to partially cover said members, the holes and leg joining element of the U-shaped member.

JOSEPH BURGER.
